UNITED STATES PATENT OFFICE

FRED C. BAUER, OF IRVINGTON, NEW JERSEY

FOUNTAIN

Application filed May 20, 1930. Serial No. 454,027.

This invention relates to an improved fountain, adapted for use in decorations, being particularly adapted for table decorations, as a center piece or as an ornamental article in other situations, such as window displays and the like.

This invention has for its object the provision of a portable fountain which uses the same water continuously thus requiring only a small quantity. Furthermore, the fountain is without any water pipe connections, having only an electrical connection to a socket and having an intermittently operated pump or ejector mechanism which receives water from the bowl of the fountain and projects it as a small stream or a jet which descends back into the bowl. The cost of operation is very slight and the device is light in weight and can be made very attractive and decorative in appearance as the mechanism is small and can be easily concealed in the fountain.

The invention also relates to certain details of construction to be more fully described herein and finally embodied in the claims.

The invention is illustrated in the accompanying drawing in which Figure 1 is a cross section of the fountain with the liquid projecting mechanism in elevation. Figure 2 is a section of the said liquid projecting mechanism. Figure 3 is a top view of the outlet of the pump or projector and Figure 4 is a section on line 4-4 in Figure 2.

The fountain itself is usually made small as for instance the kind made for use as a centre-piece for a table and comprises a basin which can be of any desired material. Metal that is lacquered or porcelain are well adapted for this use. The basin comprises a bowl 10 which is mounted on a foot or base 11. The bowl is usually shallow and does not require much water. The bowl is preferably made with a depression 12, in the centre, and this depression receives the upper part of the plunger mechanism which forms a fountain casing and comprises a head 13. The head has a reduced part 28 in the form of a boss which passes through a hole in the centre of the depression. The head comprises a casting on which is a top 16 with holes 17 to form a spray. The boss 15 has a tubular extension

18 in which slides the armature 19 of a magnet 20. The upper end of the armature projects into the head and is provided with a piston. The piston is made up of a web 22 which has openings 23 and on the top of this is the disc 24 which has a limited movement away from the web on the down stroke of the piston. This movement is limited by the head 25 on the screw 25^a which secures the web on the end of the armature. The casing of the head has openings 26 at the bottom through which openings the water passes from the bowl to replenish the head after each ejecting stroke. The magnet includes a field member 27 which is in the form of a frame and has a screw-threaded opening which is screwed on the reduced part 28 of the head of the fountain casing. The parts are thus fastened to the bowl. A gasket 29 is inserted to make the joint waterproof. The field has a coil 30 which actuates the armature in an upward direction. The armature returns to its lower position by gravity and slides freely in the extension 15. The magnet is supplied with current through an electric circuit which also includes any well-known form of make and break device, as a thermostatic plug or control 31. This control is not illustrated in detail as it is an ordinary article of commerce.

As the device operates, the current energizes the magnet which forces the projecting mechanism which sprays water through top 26 of the head 13. The contact device shuts off the current and the plunger and piston drop. The control again energizes the armature and the operation is repeated. In this way, the fountain emits water and this continues while the current is turned on.

In order to prevent a spurting of water to an excessive height and to modify or equalize the pressure on the piston to the proper extent to accomplish this I interpose a resilient or lost-motion device between the piston and the armature of the magnet. The form that is illustrated comprises a spring 32 that abuts on the lower part of the armature 19 and on the upper part 33. The extension 34 of the lower part slides in the upper part and the spring is compressed when the armature jerks upwardly. The spring is compressed when

this takes place and then expands to force the piston upwardly to expel the water in the form of a substantially steady stream.

The fountain is small and easily portable, requires no water except the original small supply and the operation takes but little current and is therefore economical.

I claim:—

1. A fountain comprising a bowl, a solenoid device including a make and break connection for operating a pump, a pump in the bottom of the bowl, the pump including a piston, the piston being secured at the end of the armature of the solenoid, and a compression spring between the piston and the armature to modify the impulse of the armature on the piston.
2. A fountain comprising a basin including a bowl and a base, a solenoid in the base, the armature of the solenoid extending into a pump mechanism to form a plunger, a pump mechanism in which said plunger reciprocates and having its inlet in communication with the basin and having its outlet disposed to form a jet in the basin when the plunger operates, an intermittent contact device in the circuit which energizes the solenoid, and a compression spring interposed between the plunger and the armature.
3. A portable fountain comprising a basin including a bowl and a base, the bowl having an opening therein, a fountain casing in the bowl and secured in the opening, the fountain casing having a jet opening therein, the fountain casing having an inlet opening for receiving liquid from the bowl, a solenoid suspended from the fountain casing, a plunger in the fountain casing and operated by the armature of the solenoid, a make-and-break device, an electric circuit including the solenoid and the make and break device, and a spring interposed between the plunger and the armature to modify the action of the armature on the plunger.
45. In testimony whereof he affixes his signature.

FRED C. BAUER.
